UNITED STATES PATENT OFFICE.

SCHUYLER VAN NESS, OF FRAMINGHAM, MASSACHUSETTS, ASSIGNOR TO DENNISON MANUFACTURING COMPANY, OF BOSTON, MASSACHUSETTS, A CORPORATION OF MASSACHUSETTS.

COIN-HOLDER.

1,114,826.

Specification of Letters Patent.

Patented Oct. 27, 1914.

Application filed January 3, 1914. Serial No. 810,134.

To all whom it may concern:

Be it known that I, SCHUYLER VAN Ness, a citizen of the United States, and resident of Framingham, in the county of Middlesex 5 and State of Massachusetts, have invented new and useful Improvements in Coin-Holders, of which the following is a specification.

This invention relates to coin holders of the class adapted and intended for the presentation in an attractive setting of a gift of a gold or silver coin. The holders heretofore generally provided for this purpose, comprise essentially a sheet of cardboard or 15 the like having an opening adapted to hold the coin. These holders of necessity have but a single coin holding opening, for obviously where a single coin is to be presented as a gift in a coin holder, the presence of other unfilled coin openings would mar the attractiveness of the setting. Because of this essential limitation to a single coin holding opening, the devices of this 20 class heretofore provided have proved unsatisfactory. Dealers have been obliged to carry in stock holders having openings of practically all the different sizes of gold and silver coins. While there is a demand through the year, the principal sale of these 25 goods is at Christmas, and as there is absolutely no way of accurately determining in advance the probable sale of any particular size in any particular season, the result has proved to be that the dealers find their supply of certain sizes quickly exhausted, while 30 many of other sizes remain unsold and have to be carried over to another season. Because of this necessity of carrying a full line with a chance of having some of the goods 35 unsold for an entire year, dealers have ordered with caution and many retailers who would naturally sell this class of goods have refrained from so doing to the obvious detriment of the manufacturer, and disappointment 40 of purchasers. Furthermore, purchasers of these holders have been obliged to determine in advance the particular coin which they intended to give if they were to be certain of obtaining a holder having an 45 opening of the proper size to fit the particular coin. Experience has demonstrated that at the time of seeking a suitable holder, many prospective givers have not determined the exact amount of money they intend 50 to give, and therefore, many sales have 55

been lost because while a suitable coin holder was desired, the prospective giver found it impossible or impracticable to determine in advance the amount of his intended gift.

It is the object of this invention to eliminate these objectionable features of the older devices and to that end to provide a coin holder which, while possessing the essential single coin holding opening, shall 60 be adapted to hold the different sized coins commonly employed as gifts.

Referring to the drawings which illustrate an embodiment of the invention,—Figure 1 is a plan view of my improved coin 70 holder showing the cover open; Fig. 2 is a section on the line 2—2 Fig. 1; Fig. 3 is a fragmentary plan view showing the coin holding opening with its lid open; Fig. 4 is a plan view of the device with the cover 75 closed; Fig. 5 is a section on the line 5—5 Fig. 4; Fig. 6 is a section on the line 6—6 Fig. 1; and Figs. 7, 8 and 9 are plan views of fillers forming a part of my invention.

A is a body of the device made of cardboard or other suitable material and provided with an opening B adapted to receive a gold or silver coin. The opening B is preferably circular in form and extends into the body A for a distance sufficient to 80 permit the coin when held therein to lie substantially flush with the face of the body A. Usually, though not essentially, the opening B extends completely through the body A and a back C is provided, secured 85 to the body A in any suitable manner, serving as one of the coin retaining walls when the device is in use. The coin holding opening B is of a size adapted securely to hold the largest coins usually given away in these 90 devices, as for example, a twenty dollar gold piece. It will be clear that such an opening is much too large securely to hold the smaller coins commonly employed as gifts, as for example, the five dollar or the two 95 and one-half dollar gold pieces. There are therefore provided fillers D of annular form adapted tightly and removably to fit within the opening B, and having coin holding recesses d to fit the coins of the various sizes 100 which are too small to be securely held within the large opening B. Preferably, there is provided a lid or closure E hinged to the body A and adapted to overlie the coin holding opening B and the filler D secured 105 110

therein. There is also preferably provided a cover F hinged to the back C and adapted to overlie the lid or closure E. The cover F is made of comparatively heavy material 5 while the closure E is made of comparatively thin material in order that the cover may lie flat upon the body A when in its closed position shown in Fig. 4. It will be apparent that both the lid or closure E and 10 the cover F serve to protect the coin to prevent its accidental dislodgment from the coin holding opening or from the recess d when a filler D is employed.

In order that the device may serve its intended purpose as a means for presenting a gift of a sum of money in an attractive form, the entire device is adapted to be decorated in a manner appropriate to the season or occasion of the gift. Thus, there is 20 shown in the drawings a coin holder embodying my invention bearing Christmas decorations both upon the back, cover and body and carrying a design which gives to the coin holder as a whole the appearance of 25 a watch box or case with a watch therein.

It will, I believe, be apparent that the provision of the fillers D for insertion in the coin holding opening B wholly remove the defects in the older construction of which 30 I have spoken. By the use of my invention dealers are no longer required to carry in stock coin holders with openings of different sizes but are enabled to carry an attractive coin holder with a single opening for the

largest sized coin, which opening by the insertion of the proper sized filler at once becomes of proper size for any particular smaller coin which the purchaser desires to give. Prospective buyers are not required to determine in advance the particular coin 35 they intend to give but may, after the purchase of the holder, determine at their leisure the exact coin to be given and then insert the proper filler to render the coin holding opening a proper one for the coin 40 determined upon.

I claim:

As a new article of manufacture, a gift coin-holder comprising body portion having a single circular coin holding opening, 50 a non-integral filler having substantially the form of an annulus and adapted to be inserted and removed from the said coin holding opening of said body without mutilation of said body or filler, the periphery of 55 said filler following a salient element of the design whereby the continuity of the design is uninterrupted by the line of cleavage, a hinged closure having its upper face provided with a design and overlying said filler 60 and opening, and a hinged outer cover overlying said closure and said body portion.

Signed by me at Boston Massachusetts this twenty-ninth day of December, 1913.

SCHUYLER VAN NESS.
